UNITED STATES PATENT OFFICE.

MITCHELL R. MANN, OF PORTLAND, OREGON, ASSIGNOR TO JAMES J. ROSS, OF PORTLAND, OREGON.

SEPARATOR.

Application filed January 14, 1922. Serial No. 529,286.

To all whom it may concern:

Be it known that I, MITCHELL R. MANN, citizen of the United States, residing at Portland, in the county of Multnomah and 5 State of Oregon, have invented certain new and useful Improvements in Separators, of which the following is a specification.

This invention relates to an improved separator and has as one of its principal objects to provide a simple, compact and efficient device of this character for separating metal particles from grain.

The invention has as a further object to provide a device that will not choke and 15 which will be adapted to handle heavy feeds as well as light and feathery feeds with equal efficiency.

And the invention has as a still further object to provide a device wherein the metal 20 particles separated from the grain will be collected and retained and wherein provision will be made whereby the device may be readily cleaned of the collected particles.

Other and incidental objects will appear 25 hereinafter.

In the drawings:

Figure 1 is an elevation of my improved separator showing the device in connection with a mill of conventional design,

30 Figure 2 is a sectional view on the line 2—2 of Figure 3, looking in the direction of the arrows.

Figure 3 is a section on the line 3—3 of Figure 2, looking in the direction of the arrows,

35 Figure 4 is a section on the line 4—4 of Figure 3, looking in the direction of the arrows, and

Figure 5 is a perspective view showing one 40 of the separate plates in detail.

Referring now more particularly to the drawings, I have shown my improved separator in connection with an ordinary mill 10 having an intake spout 11 and provided with a drive shaft 12 with which are coupled motors 13, all of this structure being well known. In carrying the invention into effect, I employ a preferably rectangular casing 14 which is secured upon the spout 11 45 to communicate at its lower end therewith, and leading into the upper end of the casing is a chute 15. The casing may be formed of wood or other approved material and secured to the bottom wall of the casing are 50 hinge brackets 16 depending at their for-

ward ends beneath the casing flush therewith. Mounted to swing upon the depending forward end portions of said brackets is a preferably metallic frame 17 and suitably secured to said frame is the front side 60 wall 18 of the casing. This front side wall is formed of composition board or other approved insulating material and mounted thereon is the magnet assembly employed, the wall being, as shown in Figure 1, normally held to close the casing at its forward side by appropriate catches 19.

Formed in the wall 18 of the casing are, as particularly shown in Figure 4, staggered pairs of spaced transverse slots 20 and 70 slideable in each pair of slots is a core bar 21 carrying a magnet winding 22. At their ends, each of the core bars is, as particularly shown in Figure 3, bent to provide a pair of laterally directed arms 23 extending freely through a pair of said slots respectively while near their inner ends, the arms are formed with offsets 24 abutting the outer face of the wall 18 for limiting the arms 75 in their movement through the slots and sustaining the windings 22 in spaced relation to the wall. Fixed upon the arms to overlie the slots 20 at the inner face of the wall 18 are closure plates 25 and mounted upon the wall at its outer side to rest against said arms overhanging the ends of the core bars 21 are angle shaped clamping plates 26. These latter plates are secured to the wall 18 by bolts 27 which are preferably equipped with wing nuts.

80 Mounted upon each pair of arms 23 at the inner side of the wall 18 is, as particularly shown in Figure 2, a pair of pole plates 28, the several plates being staggered with respect to each other in vertical relation. As 85 best shown in Figure 5, the pole plates are substantially triangular in general contour and are each preferably formed from a piece of suitable resilient sheet metal bent to define a base flange from which rises a rear 90 side flange and extending from the rear side flange is an elongated front flange inclining downwardly below the base flange to define a baffle 29. The base flanges are, as shown in Figure 2, riveted or otherwise secured to 95 the arms 23, the baffles 29 of one pair of arms confronting, of course, the baffles of the other pair of arms and, as will be observed, said baffles are bent rearwardly at their lower margins to define channel shaped col- 100 105 110

lecting lips 30. As best shown in Figure 2, the pairs of pole plates are arranged at opposite sides of the inlet opening through the top wall of the casing and secured 5 against the inner face of said wall is a guard member 31 for directing the grain between the baffles. Fitting in the frame 17 to rest against the outer side of the wall 18 is a cover 32 enclosing the magnet windings 22 10 and associated parts, the cover carrying angle plates 32' through which are engaged suitable bolts detachably connecting the cover with the frame.

The magnet windings 22 may be connected 15 in series and mounted upon the casing is, as shown in Figure 1, an appropriate switch 34 for controlling the flow of current through said windings. In any instance where current of suitable voltage is available as, for instance, a 110 volt lighting circuit, the magnets may be connected with 20 said circuit. However, where a proper current supply is not available, I employ a generator 35. This generator may be of any 25 approved type and mounted upon the drive shaft 12 of the mill is a pulley 36 about which is trained a belt 37 for driving the generator. Thus, as long as the mill is running, current will be supplied to the magnets.

As will now be readily understood in view of the preceding description, when a circuit is closed through the magnet windings 22, the pole plates 28 will be energized and, as will be observed, these plates are so arranged that the grain stream from the chute 15 will flow over each of the baffles 29 of the plates successively. All metal particles in the grain will thus be separated therefrom, the metal particles clinging to 40 the baffles. These metal particles will, due to the action of the grain in passing therover, be caused to slide down the baffles and under the lower ends thereof to be collected upon the lips 30 out of the path of the grain stream. Accordingly, the metal particles will, after having been once separated from the grain, be prevented from being dislodged from the baffles to become again mixed with the grain and at suitable intervals the collected particles upon the lips 30 may be removed by simply releasing the catches 19 and swinging the front wall 18 of the casing outwardly when access may be conveniently had to the pole plates. In this connection, 50 it is to be observed that by providing the depending hinge brackets 16 the wall 18 and magnet assembly will swing in a wide arc, necessitating correspondingly less clearance at the upper end of the casing while 55 feed and other particles will be prevented from collecting between the wall 18 and the casing to hamper the closing of said wall against the casing, it being possible to move the wall to a position spaced from the casing 60 so that feed in the casing may be brushed

out at the bottom thereof between the casing and said wall.

I accordingly provide a particularly efficient device for the purpose set forth and attention is now directed to the fact that by 70 removing the cover 32 and loosening the bolts 27 of the clamping plates 26, the arms 23 of the core bars 21 may be shifted within the slots 20 of the wall 18 for adjusting the pairs of pole plates either toward or away 75 from each other. These pole plates may thus be conveniently positioned for the passage of a heavy grain therebetween or the passage of light and feathery feed therebetween. The device is accordingly adapted for a wide 80 range of use.

Having thus described the invention, what is claimed as new is:

1. A device of the character described including a casing having a hingedly mounted 85 door normally closing the casing, and magnetic pole plates carried by said door and shiftably supported thereby housed within the casing to intercept a stream of material flowing therethrough, the door being movable to open position for shifting the pole pieces from within the casing and exposing said plates.

2. A device of the character described including a casing, magnet core bars each having spaced arms extending through a wall 95 of the casing, and pole plates mounted upon the arms within the casing to intercept a stream of material flowing therethrough the arms being shiftable upon the casing for 100 adjusting the plates of one core bar with respect to the plates of the other core bar.

3. A device of the character described including a casing having a wall provided with slots, magnet core bars having arms extending freely through said slots, pole plates carried by the arms within the casing to intercept a stream of material flowing therethrough, the arms being adjustable within 105 said slots for positioning the plates toward or away from each other, and means carried by said wall for securing the arms in adjusted position.

4. A device of the character described including a casing having a wall provided with slots, magnet core bars having arms extending through said slots into the casing, pole plates mounted upon the arms within the casing to intercept a stream of material flowing therethrough, the arms being adjustable within the slots for positioning the plates toward or away from each other, and clamping plates mounted upon 120 said wall to coact with the arms for clamping said arms in adjusted position.

5. A device of the character described including a casing, and a magnetic pole plate mounted therein to intercept a grain stream flowing through the casing and provided with a channeled collecting lip.

6. A device of the character described including a casing, and a magnetic pole plate mounted therein to intercept a grain stream flowing through the casing and bent at its lower margin to provide a trough shaped collecting lip lying behind the plate. 35
7. A device of the character described including a casing, depending brackets carried thereby, a door normally closing the casing, means swingingly supporting the door upon said brackets, and magnetic pole plates shiftably supported by the door normally disposed within the casing, the door being movable to open position for shifting the pole plates from within the casing and exposing said plates. 40
8. A device of the character described including a casing having a wall thereof provided with openings, core bars having arms extending through said openings into the casing and provided with shoulders, means clamping said shoulders against the wall securing the core bars in position, and pole plates carried by the arms within the casing. 45
9. A device of the character described including a casing having a wall thereof provided with openings, core bars having arms extending through said openings and provided with offsets, plates clamping said offsets against the wall securing the core bars in position, and pole plates carried by the arms within the casing. 50
10. A device of the character described including a casing, pole plates therein, and means extending through a wall of the casing supporting said plates and slidable upon said wall for adjusting the plates with respect to each other. 55
11. A device of the character described including a casing, pole plates therein, and arms extending through a wall of the casing supporting said plates and slidable upon said wall for adjusting the plates with respect to each other. 60
12. A device of the character described including slidably mounted core bars having arms, and pole plates carried by said arms and arranged to direct material traveling over the plates from each plate toward the next successively, the core bars being shiftable for adjusting the plates rectilinearly toward or away from each other to vary the distance between successive plates. 65
13. A device of the character described including slidably mounted core bars having arms, and angularly disposed pole plates carried by the arms and arranged to direct material traveling over the plates from each plate toward the next successively, the core bars being shiftable for adjusting the plates with respect to each other to vary the distance between successive plates without changing the angle of said plates. 70

In testimony whereof I affix my signature.

MITCHELL R. MANN: [L.S.]
